UNITED STATES PATENT OFFICE.

WILLIAM SELLERS, OF PHILADELPHIA, PENNSYLVANIA.

IMPROVEMENT IN APPARATUS FOR PUDDLING IRON.

Specification forming part of Letters Patent No. 124,224, dated March 5, 1872.

To all whom it may concern:

Be it known that I, WILLIAM SELLERS, of the city and county of Philadelphia, in the State of Pennsylvania, have invented certain new and useful Improvements in the Mechanical Puddling of Iron, the following being a specification of my said improvements.

My improvements relate to that class of puddling-machines in which the process is effected by revolving the chamber or vessel which contains the metal to be operated upon in such a manner as to present a constantly-changing surface of the contained metal to the action of flame.

Heretofore, in all machines in which puddling has been thus effected, the flame has been passed into, through, and out of the chamber or vessel in the direction of the axis of the vessel, the respective openings for the entrance and the exit of the flame being opposite each other. In my improved machine, on the contrary, the flame passes into the puddling-chamber or vessel in the direction of its axis; but, instead of passing through and out of the chamber, as above-described, it sweeps over the whole of its interior surface, and returns to and passes out of the opening in the chamber at which it entered, thus operating upon the contained metal more economically and more effectually.

Again, in order to charge or to discharge revolving puddling-chambers or vessels, as heretofore constructed and used, it has been necessary with some of them to have a portion of the flue leading to the chimney removable, while with others it has been necessary to lift the vessel from its place. In my improved machine, on the contrary, the delivering and the discharging flues for the flame are arranged in the same vertical plane, and the revolving-chamber or vessel is supported upon a traversing-frame, which, by preference, vibrates through an arc of a circle about a vertical axis, the axis of the revolving vessel being tangential to the arc of vibration of the frame, so that the vessel may be swung round out of its normal operative position, in which its axis is perpendicular to the vertical plane of the flues until its axis is brought parallel or nearly so with the vertical plane of the flues, in which latter position the mouth of the vessel is accessible for the perfectly-convenient charging

or discharging of the metal without either removing any part of the flue or lifting the vessel, as heretofore. Moreover, in my improved machine the frame which supports the revolving vessel also carries the mechanism for revolving it; and, by preference, the steam for operating this mechanism is carried through the vertical axis about which the frame vibrates, as before mentioned; and this constitutes an additional feature of my improvement.

Again, to attain in the operation of such a vessel the highest mechanical perfection it is necessary to provide against anything which might, even in degree, detract from its efficiency; and as the variations of temperature inseparable from the operation might disturb the proper relation of the parts, I provide for such adjustments of the frame which carries the vessel as will compensate any such disturbance.

The accompanying drawing illustrates the means which, by preference, I have adopted for attaining the objects of my improvements.

Figure 1 is a sectional view of a puddling-furnace embodying my improvements. Fig. 2 is a plan of the puddling-machine, furnace-flues, and chimney, showing in dotted lines the vessel or chamber in position for being charged or discharged. Fig. 3 is an elevation of the parts shown in Fig. 2. Fig. 4 is a sectional view of my improved puddling-machine in combination with a furnace.

The chamber or vessel A has, by preference, a spherical form, with a large mouth or circular opening, B, and has on its exterior a series of bosses or projections, c c, opposite the opening B, so arranged as to serve for securing a worm-wheel, D, to the chamber. To the worm-wheel D the hollow trunnion C is attached, which supports the chamber at that end, (the axis of this trunnion being substantially horizontal and passing through the center of the opening B.) Motion is imparted to the vessel through the worm-wheel D by means to be presently described. The object of using a hollow trunnion and bosses on the chamber is to provide for a circulation of air, which will prevent the overheating of the journal. A steel band or tire, F, is to be shrunk upon the vessel A near its open end, and concentric with the trunnion C. This vessel should be lined with some refractory material, such as is tech-

nically known in the art as a "fix," which will withstand the heat and the chemical and mechanical actions involved in the process. A tap hole, *q*, passing through the vessel and through the lining, serves for withdrawing the cinder from the vessel. This tap-hole is, of course, plugged up properly during the operation of the vessel, and at all other times, except when opened for the purpose of withdrawing the cinder. A suitable floor-plate, *j*, is provided in the proper relation to the delivering and discharging flues, and of sufficient area for the traverse of a large hollow frame, *H H H*, which has three points of support upon the floor-plate—namely, at what I may call the inner end of this frame a pintle, *h*, resting in a step-bearing, *I*, about the axis of which the traversing-frame moves in carrying the chamber or vessel *A* from one to the other of the two positions shown in Fig. 2; and at the outer and rear ends, respectively, of the frame the two truck-wheels, *i i'*, running upon the floor-plate *j*. The axles *k k'* of these truck-wheels are placed radially to the axis of the pintle *h*, and have their bearings in vertically-adjustable boxes *l l'*. The pintle *h* is also made vertically adjustable in this instance by being provided with a large screw-thread, which enters a corresponding thread in the frame *H H H*, so that, by turning the pintle within its screw-socket, the frame may be raised or lowered at will, and this pintle is fixed in its vertically-adjusted position by a set-screw. The bolt-holes provided in the floor-plate *j* and in the flange of the step-bearing *I* for the holding-down bolts *o o o* of the step-bearing are made oblong in directions at right angles to each other, so as to admit, also, of an adjustment of the frame horizontally in every direction by moving the step-bearing. Upon the axle *k'* of the truck-wheel *i'* I fasten securely a bevel-wheel, *m*, into which gears the pinion *n*, securely fastened upon the vertical shaft *M*, which is supported by the box *l'* and case *G*, and upon the upper end of which I place the hand-wheel *N*. The frame *H H H* can be readily moved into either of the positions shown in Fig. 2 by rotating the hand-wheel *N* in the requisite direction, thereby causing the truck-wheel *i'* to revolve, the frictional contact between this wheel and the floor-plate *j* being sufficient to vibrate the frame *H H H* about the pintle *h*. In the front cross-piece of the frame *H H H* I mount the guide-wheels *f f*; and at or near the rear of the frame I mount a casing, *G*, in which I provide a bearing for the trunnion *C*, and also a bearing for the shaft *e* of a worm, *E*, which engages in the worm-wheel *D* on the chamber *A*. This casing *G* incloses both the worm-wheel *D* and the worm-shaft *e*, protecting them from dust and admitting of their being kept thoroughly lubricated. The vessel *A* is placed upon the frame *H H H*, with its trunnion resting in its bearing in the casing *G*, and thus supporting the rear end of the vessel, while the guide-wheels *f f*, upon which the band or tire *F* rests and turns, support the forward or open end of the vessel in a position

always substantially horizontal; and the vessel thus supported is free to be revolved upon its points of support through the worm-wheel.

Motion is communicated to the vessel *A* from a steam-engine having the axis of the cylinder horizontal, and over the axis of the pintle *h*. The connecting-rod from this steam-cylinder takes hold upon a crank-pin in the face of the balance-wheel *O* upon the outer end of the worm-shaft *e*. Steam is carried to this engine by a vertical steam-pipe in the line of the axis of the pintle *h*, and the exhaust is carried off through this pintle, so that the vibrations of the frame *H H H* cause no disturbance to either the steam or the exhaust-pipe.

I have not shown this steam-engine in position, as neither it nor its arrangement forms any part of my claim, and as it will be obvious to a skilled mechanic that, by various methods other than the one described, the vessel *A* may be rotated, the axis of vibration of the frame *H H H* still serving as a point at which to introduce the power.

It will also be evident to the skilled mechanic that the frame which carries the puddling-vessel, and the mechanism for revolving the same, may be arranged in many other ways to perform the functions of moving the puddling-vessel to and from the flues without disarranging the driving mechanism: thus, it may be mounted upon wheels on a track, either straight or curved, which may carry the vessel to a convenient point for charging and discharging, or the track may be upon a turning table, so that the vessel may be moved first at right angles to the plane of the flues, and then turned around to a convenient position for charging and discharging; and I contemplate arranging this frame to traverse in such various directions as the exigencies of the case may require without disturbing the connection between the driving mechanism upon the frame and the motive power. The course by which the flame enters and is discharged from the revolving puddling-chamber *A* is very clearly exhibited by the arrows in Figs. 1 and 4. I provide a door, *W*, at the back of the flues, through which the chamber, when in position, may be fettled or its charge rabbed, and a spy-hole, *v*, in this door to observe when the charge of metal is in condition to have the cinder withdrawn.

The mode or means by which the requisite flame used in the puddling process is to be produced forms no part of this patent, and I need not therefore describe herein the furnace represented in Fig. 4, but in all cases the openings through which the flame or gaseous fuel and the products of combustion are respectively delivered into and discharged from the vessel should be so arranged relatively to each other that they may be encircled by a flat ring, *R*. The surface of this ring is made sufficiently broad to correspond with the surface of the open end of the vessel *A*, so that when the vessel is brought up to the ring these broad surfaces, without being in actual contact, will be so close together as to prevent the escape of

flame between them. The back of the ring R is so secured to the casing of the flue as to prevent the escape of gas on that side. This ring may be kept cool by the introduction of water into pipes cast within it, or may be simply cast hollow and water introduced at the bottom and allowed to flow off at the top. It is obvious that, instead of the plane surfaces above described, the surface of the ring and the face of the open end of the vessel might be made in various corresponding forms to effect the same object.

Assuming the vessel A to be in the position shown by dotted lines in Fig. 2, the crude iron may be charged into it either cold or in a state of fusion. The vessel is then brought around with its open end against the ring R, and the flame or gaseous fuel admitted to the vessel. If the iron is charged in cold the vessel remains stationary until the charge is brought to a state of fusion. Assuming the iron to be in a state of fusion, the vessel is revolved slowly, while a continuous volume of flame is discharged into it through the delivery-flue S. This flame sweeps over the interior surface of the vessel and impinges upon the metal, (the surface of which is being constantly changed by the revolution of the vessel,) the products of combustion continuously passing through the discharge-flue T. In Fig. 1 the arrows show the directions of the flame into and of the products of combustion out of the vessel. The successive changes of the condition of the metal during the process are readily observed through the spy-hole v in the door W, and controlled by regulating the volume and intensity of the flame and the speed of rotation of the vessel. When the balling is completed the flame is checked. The frame H H H with its revolving chamber A is swung away from the ring R by means of the hand-wheel N and its driving-gear, and the ball is removed; a new charge of crude iron being supplied, the open end of the vessel is again brought against the ring, and the operation of puddling is repeated.

The advantages of passing the flame into and out of the revolving chamber at one and the same opening are numerous. When the vessel has two openings, as heretofore, the escape of gas at each of them must be provided against, and this involves the necessity of adjustments not only between the ends of the puddling-chamber and the flue, respectively, but also between the furnace and the flue relatively to each other; so that the requisite adjustments cannot be obtained by any adjustment of the puddling-vessel alone; while with my improvements the provision against the escape of gas and all the adjustments required are confined to the single surface of the open end of the vessel. There being but one opening, the chance for escape of gas is diminished at least one-half; and there being but one surface, all the adjustments required may be made without any adjustment of the furnace or flue relatively to each other. The flame is also more perfectly reverberated and utilized, and in its pe-

culiar sweeping action over the whole interior surface of the revolving chamber operates more effectually upon the charge of metal than it could in passing directly through the vessel, as heretofore.

Charging and discharging the puddling-chamber without having to lift it, and without having to remove a portion of the flue for this purpose; having the step which carries the vertical axis of the vibrating frame adjustable horizontally in every direction, and the frame adjustable vertically upon the axis about which it vibrates, and the wheels which support the vibrating frame at other points than the axis also adjustable vertically, all of these movements and adjustments being made without disturbing the connections between the vessel, the frame, the revolving mechanism, and the power, are severally and collectively advantages which must be readily appreciated.

I claim as my invention, and desire to secure by Letters Patent—

1. The improvement in the art of mechanical puddling, hereinbefore set forth, by delivering the flame into and discharging the products of combustion from one and the same end of a revolving puddling-vessel.

2. A revolving puddling-vessel having its axis substantially horizontal and a single opening, through which opening the flame is delivered into and the products of combustion are discharged from said vessel in the direction of its axis, substantially as hereinbefore set forth.

3. The combination of a revolving puddling-vessel having its axis substantially horizontal, and flues through which, respectively, the flame is delivered into and the products of combustion are discharged from one and the same end of the revolving vessel, substantially as set forth.

4. The combination, with a revolving puddling-vessel, of a traversing supporting-frame, substantially as hereinbefore set forth.

5. The combination of a revolving puddling-vessel and a traversing supporting-frame with flues, through which, respectively, the flame is delivered into and the products of combustion are discharged from one and the same end of the revolving vessel, substantially as hereinbefore set forth.

6. The combination of a revolving puddling-vessel, a traversing supporting-frame, and mechanism by which the frame may be adjusted vertically and horizontally in every direction, substantially as set forth.

7. The combination, substantially as hereinbefore set forth, of a revolving puddling-vessel, a traversing supporting-frame, and mechanism for revolving the vessel, such revolving mechanism being mounted upon the traversing supporting-frame.

8. The combination of a revolving puddling-vessel, a traversing supporting-frame, mechanism for revolving the vessel, (such revolving mechanism being mounted upon the traversing supporting-frame,) and flues through which, respectively, the flame is delivered into and the

products of combustion are discharged out of one and the same end of the revolving vessel, substantially as hereinbefore set forth.

9. The combination of a revolving puddling-vessel having its axis substantially horizontal, a traversing supporting-frame, mechanism by which the traversing supporting-frame may be adjusted vertically and horizontally in every direction, mechanism for revolving the vessel, (such revolving mechanism being mounted upon the adjustable traversing supporting-frame,) an axis about which the adjustable traversing supporting-frame vibrates, and

through which the power for revolving the vessel is transmitted, and flues through which, respectively, the flame is delivered into and the products of combustion are discharged out of one and the same end of the revolving vessel in the direction of its axis, substantially as hereinbefore set forth.

10. In combination with a revolving puddling-vessel the bosses and hollow trunnion, substantially as and for the purposes set forth.
